UNITED STATES PATENT OFFICE.

GUSTAV LADISCH, OF STETTIN, PRUSSIA, GERMANY.

LEVELING ATTACHMENT FOR TABLES, &c.

SPECIFICATION forming part of Letters Patent No. 299,651, dated June 3, 1884.

Application filed April 12, 1884. (No model.)

To all whom it may concern:

Be it known that I, GUSTAV LADISCH, a subject of the King of Prussia, Germany, residing at the city of Stettin, in the Kingdom of Prussia, Germany, have invented certain new and useful Improvements in Leveling Attachments for Tables and other Furniture, of which the following is a specification.

This invention has reference to an improved leveling attachment to the legs of tables, chairs, and other pieces of furniture, whereby the length of the same can be adjusted accurately to unevenness of the floor, so that the annoying shaking of the tables, chairs, &c., may be avoided.

The invention consists of a socket attached to the legs of a table, chair, or other piece of furniture, said socket guiding a vertically-sliding bolt serrated at one side, which bolt is locked, after adjustment in the socket, by the toothed head of a spring-actuated pin, as will appear more fully hereinafter.

In the accompanying drawings, Figure 1 represents a perspective view of a table with my improved attachment. Figs. 2 and 3 are respectively a vertical central section and a horizontal section of the attachment as applied to square legs. Figs. 4 and 5 are a vertical central section and a horizontal section of the attachment as applied to a round leg. Figs. 6 and 7 are detail sections of a modified form of the attachment; and Fig. 8 is a sectional side view of the leveling-bolt with a caster attached thereto.

Similar letters of reference indicate corresponding parts.

a in the drawings represents a metallic socket, that is attached by screws or otherwise to the end of the leg *A* of a table, chair, or other piece of furniture. *b* is a slide bolt that is guided in the downwardly-extending socket *a*, and prevented from turning on its axis by a tongue or spline, *d*, that slides in a corresponding groove of the socket *a*. The slide-bolt *b* is flat at one side and serrated at the

flat portion. A serrated head, *e*, of a horizontally-guided pin, *f*, is pressed by a spiral or other spring, *g*, against the serrated side of the slide-bolt *b*. The outer end of the pin *f* is provided with an enlargement or button 50 that serves as a handle. When the pin *f* is drawn back against the tension of the spring *g*, the slide-bolt *b* drops by its own weight until it rests on the floor. On releasing the pin *f* the serrated head *e* is thrown into the teeth 55 of the slide-bolt, so as to lock the same rigidly in position. The slide-bolt *b* can thus be locked in any desired position by the serrated head *e*.

If the legs of the table are provided with the leveling attachments described, and the floor be uneven, it is simply necessary to withdraw the pin *f* of the attachment of that leg which does not fully rest on the floor, whereby the slide-bolt *b* is dropped down from the 65 socket until it rests on the floor, after which it is locked by the head *e* of the pin *f*. The slide-bolt *b* may be of round or other cross-section, and provided with a caster, as shown in Fig. 8; or the bolt *b* may be provided with 70 a cup-shaped enlargement, *i*, attached thereto, as shown in Fig. 6.

Having thus described my invention, I claim as new and desire to secure by Letters Patent—

The combination of the leg *A* of a table or 75 other piece of furniture, a socket, *a*, attached to the leg, a slide-bolt, *b*, guided vertically in said socket and provided with serrations at one side, and a horizontally-guided and spring-actuated pin, *f*, having a toothed head, *e*, interlocking with the serrated bolt, substantially as set forth.

In testimony whereof I have signed my name to this specification in the presence of two subscribing witnesses.

GUSTAV LADISCH.
